UNITED STATES PATENT OFFICE.

WILLIAM J. HENRY, OF PORTLAND, MAINE.

TRUNK-FASTENING.

SPECIFICATION forming part of Letters Patent No. 244,750, dated July 26, 1881.

Application filed August 26, 1880. (Model.)

To all whom it may concern:

Be it known that I, WILLIAM J. HENRY, of 5
Portland, in the county of Cumberland and
State of Maine, have invented certain new and
useful Improvements in Trunk-Fastenings;
and I hereby declare the following to be a full,
clear, and exact description of the invention,
which will enable others skilled in the art to
which it appertains to make and use the same,
reference being had to the accompanying drawings,
10 forming part of this specification, in
which—

Figure 1 is a view of the entire device when
open. Fig. 2 is a section of the same when
closed. Fig. 3 is a section of the same when
15 open.

The same letters show like parts.

My invention relates to improvements in
trunk-fastenings.

20 The object of my invention is to provide a
secure and convenient fastening; to produce
a fastening in the use of which the lid may be
drawn down by a lever in the act of closing
the said lid to the body, and also one by which the
25 lid may be held at any point of partial closing.

A is a plate to be attached to the lid of a
trunk. B is the part to be fastened upon the
body of the trunk. C is a tongue composed of
30 two parts, and attached by a hinge to the
plate A. d and f are the two parts of the
tongue C, and these two parts are connected
together by a hinge. g is a slot in the part B.
h is a spring in the slot g. i is a prolongation
35 of the part d of the tongue C beyond the hinge,
by which the parts d and f are held together.
j is a slot in the under side of the part f of the
tongue, in which the prolongation i fits. l is
the fulcrum of the part d of the tongue, and is
40 placed in the slot g, where it is rigidly attached.
The end of the prolongation i is curved so as
to form a hook bending upwardly. The device l
is also formed into the shape of a hook curving
downwardly, so that these two can be hooked
45 into each other when the tongue C is being
brought down to the slot in the plate B and
into the slot g in the act of closing the lid of
the trunk.

When the trunk-lid is opened or lifted the
50 tongue C will swing upwardly for a certain
distance, and then the two hooked ends—to wit,
the hooked end of the prolongation i and the
hooked end of the device l—will be disengaged

in order to permit the turning up or back or
complete the opening of the lid.

When the trunk is closed it is locked by 55
means of a lock in the lower end of the plate
B, the bolt of which lock plays into an open-
ing in the lower end of the tongue C. When
this lock is unlocked the spring h will throw
60 the tongue C out of the slot g.

When the trunk is to be closed and locked
the curved ends of the parts i and l are first
hooked into each other. This will bring the
tongue C into a position, as illustrated in Fig.
3, where the part d of the tongue is turned up
65 on the hinge, which unites it with the part f
of the tongue. The part d of the tongue then
becomes a lever with its fulcrum, as described,
at the hooked ends of the prolongation i and
of the fulcrum l, with the weight to be moved
70 represented by the trunk-lid. The power is
applied on the tongue C. By bearing down
with the hand upon the part d of the tongue
C, which is composed of the parts d and f, the
trunk-lid is brought down upon the body until
75 the tongue C is pressed into the slot g in the
plate B. This closes the trunk, and it is then
locked by the bolt of the lock in the lower end
of the plate B entering the opening in the
lower end of the tongue C. The trunk-lid can
80 be held at any desired position short of being
completely closed upon the body. This is done
by pressing lightly with the hand on the tongue
C, or part d thereof. Thus while the lid is held
partially closed by one hand the other may be
85 employed in pushing into the trunk any arti-
cles not in place in the trunk, or which pro-
trude through the opening between the lid and
the body, and would, if so left, prevent a com-
plete shutting of the trunk.

90 o are two projections on the under side of
the part d of the tongue, which projections,
when the part d is dropped into the slot g, pass
over the cross-piece p, and thus hold down the
lid and take the strain of it, if the trunk is so
95 full that the lid has a tendency to fly open.
The prolongation i also, resting in the hook l,
aids in this object when the tongue C is flat
down in the slot g.

When the lid of the trunk is raised the tongue
C rises with the lid and is never detached from
it, the unlocking merely permitting the tongue
to rise out of the slot g.

8 shows the position of the lock, and it is in

a covered part of the part B and at its lower end. The bolt of the lock works into the opening *t* in the lower end and edge of the part *d* of the tongue C.

5 I do not claim a trunk-closing device having a lever hinged to a trunk-body and another lever hinged permanently to the first, which second lever must be unhooked or detached from the trunk-lid in order to open the trunk.

10 What I claim as my invention, and desire to secure by Letters Patent, is—

In combination with a trunk and lid, the

part A, slotted plate or part B, tongue C, composed of the parts *d* and *f*, spring *h*, prolongation *i*, hook *l*, projections *o*, cross-piece *p*, lock *s*, and opening *t*, as and for the purposes herein set forth.

In testimony that I claim the foregoing as my own I affix my signature in presence of two witnesses.

WILLIAM J. HENRY.
